COMBINATION HINGE AND LATCH

Nathan J. Kroll and Samuel Kroll, Chicago, Ill.

Application December 30, 1935, Serial No. 56,671

5 Claims. (Cl. 16—146)

This invention relates to a combination hinge and latch.

It is an object of this invention to provide an improved combination hinge and latch which is relatively simple and inexpensive in construction and efficient in use.

Another object of the present invention is to provide a novel combination hinge and latch for hingedly interconnecting, and releasably latching together, the collapsible or movable parts or sections of a collapsible or folding piece of furniture such, for example, as a collapsible child's play crib.

A further object of the present invention is to provide a novel combination hinge and latch by means of which two movable parts or members may be hingedly connected, and at the same time, releasably latched together.

Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is a perspective view showing a preferred form of the new combination hinge and latch as used in conjunction with a collapsible or folding piece of furniture, which is shown as having the form of a child's play crib;

Fig. 2 is a fragmentary top plan view showing the child's play crib, with which the new hinge-latch is associated, in collapsed or folded position;

Fig. 3 is a side elevational view on line 3—3 in Fig. 1, illustrating the operation of unlatching the new device;

Fig. 4 is a top plan view of the new device showing the same in latched position;

Fig. 5 is a top plan view showing the new device in unlatched position; and

Fig. 6 is a sectional view on line 6—6 in Fig. 5.

Fig. 7 is a side elevational view similar to Fig. 3, and is taken in the direction of line 7—7 of Fig. 4.

A preferred form of the present invention is shown in the drawing, is therein generally indicated at 10, and is shown as associated with a collapsible or folding piece of furniture which is shown having the form of a child's play crib 11, which includes a wall 12 which includes two collapsible parts or sections 13.

The new combination hinge-latch 10 comprises two hinge sections or plates 14 and 15 which are adapted to be attached to the movable parts or sections 13 of the wall 12 by means of fastening

elements which are shown as having the form of screws 16, or the like, these two hinge sections or plates 14 and 15 being hingedly or pivotally connected together, as at 17.

Formed in the hinge plate or section 15 is an upward extension in the form of a latch keeper 18 and mounted on the hinge plate or section 14 is an upright pin or post 19. Arranged upon this upright pin 19 is a coil spring 20 and slidably mounted upon the pin or post 19 is a latch member or bolt 21, this latch member or bolt 21 having an offset portion 22 which provides a handle. This latch bolt or handle 21 has an end portion 23 in which is formed a notch 28 and this notched portion 28 of the latch bolt 21 is latchingly engageable with the keeper 18, it being noted that the notched end portion 23—28 of the latch member 21 is normally urged, by the spring 20, into effective position, (downwardly, Fig. 7, upwardly, Fig. 3), into the position in which it is shown in full lines, Fig. 3, and in which position the body of the latch member 21 is disposed parallel to and against the hinge plates or sections 14 and 15.

Formed on the hinge plate or section 14 are two spaced and upwardly extending guides 24 and 25 and the latch bolt 21 projects between these guides 24 and 25 and is prevented by the same from lateral movement, that is, from turning about its pivot 17.

Formed on the latch keeper 18 is a beveled cam edge 27 and engageable with this beveled cam edge 27 of the keeper 18 is an upwardly angled end portion 26 of the latch bolt 21.

It will be noted by reference to Figs. 3 and 7 that the end portion 29 of the handle 22 of the latch bolt 21 is normally disposed in spaced relationship (as in full lines, Fig. 3), which respect to the hinge plate or section 14.

Operation

In the use of the new combination hinge-latch the same may be mounted in effective position, that is, in position of use, by attaching the hinge or mounting plates 14 and 15 to the collapsible or folding sections 13 of the article 12, in the manner shown, that is, by attaching the mounting or hinge plate 14 to one of the sections 13 of the crib 12, and attaching the mounting or hinge plate 15 to the other section 13 of the play crib 12.

When the new hinge-latch is thus mounted in position of use it will act both as a hinge for hingedly connecting the sections 13 of the play crib 12 together and will also act as a latch for releasably latching the hinge sections 13 together, it being noted that the latch bolt 23 nor-

mallly engages the keeper 18 and prevents the sections 13 of the article 12 from being moved into extended position relative to each other.

The latch bolt 21 may be moved out of latching engagement with the keeper 18 by manually grasping the handle portion 22 of the latch bolt 21 and pressing downwardly upon the same, (as seen in Fig. 7), thereby pivoting the latter bolt 21, against the action of the spring 20, (from full to dotted line position, (Fig. 3), thereby moving the end portion of the handle 22 into engagement with the hinge plate 14, whereupon the parts 13 and the hinge sections or plates 14 and 15 may be moved, relative to each other, about the pivot 17, it being noted that when the end portion 23 of the latch bolt 21 is pivoted from latched into unlatched position (from full to dotted line position, Fig. 3), the notched end portion 23-28 of the latch bolt 21 may be moved past the latch keeper 18, and the parts 13 and hinge plates 14 and 15 thus moved into the position in which they are shown in Fig. 5, that is, into open or extended position.

When the collapsible parts or sections 13 are moved back into closed position, relative to each other, (as in Fig. 4), the upwardly angled end portion 26 of the latch bolt 21 will engage the beveled cam edge or striker portion 27 of the latch keeper 18, whereupon the said angled end portion 26 of the latch bolt 21 will ride up the cam edge 27 of the latch keeper 18, against the action of the spring 20, thereby pivoting the latch bolt 21 from full to dotted line position, Fig. 3, the latch bolt 21 thus moving into effective or latched position, as shown in Figs. 3, 4 and 7, it being noted that when the latch bolt 21 is thus positioned it is prevented from lateral movement, relative to the keeper 18, by the guide members 24 and 25.

40 It will be seen from the foregoing description that the present invention provides a new article of manufacture which possesses a double utility or purpose, namely, it acts both as a hinge and as a latch, for hingedly interconnecting and releasably latching together two separable or movable parts such as the collapsible rails or sections of a wall of a child's play crib, or similar article, as shown.

While we have illustrated and described the 50 preferred form of construction for carrying our invention into effect, this is capable of variation and modification, without departing from the spirit of the invention. We, therefore, do not wish to be limited to the precise details of construction set forth, but desire to avail ourselves of such variations and modifications as come within the scope of the appended claims.

Having thus described our invention, what we claim as new and desire to protect by Letters Patent is:

1. A combination hinge-latch, comprising two hinge plates or sections, means for hingedly or

pivots connecting the said hinge plates or sections together, means for releasably latching the said hinge plates or sections in closed position relative to each other, said second-named means including a latch keeper on one of said hinge plates, a pin or post upon the other of said plates, a latch member or bolt pivotally mounted between its ends upon said pin or post for vertical rocking movement relative thereto, and a spring yieldably urging said latch bolts against the second-named plate, said latch bolt having a handle portion for moving the said first-named portion thereof, against the action of said spring, out of latching engagement with said keeper.

2. A combination hinge latch comprising two hinge plates, means hingedly connecting said plates, a latch keeper on one of said plates, a latch member on the other said plate in the form of a substantially flat elongated arm having an apertured portion intermediate its extremities and having a handle portion formed in one of said extremities, the said other plate having a pair of extensions flanking the said latch member and a headed pin extended through the said apertured part of said latch member and having a spring thereon with its end portions bearing against the said headed portion and an upper surface of said latch member.

3. A combination hinge latch comprising first and second hinge plates, means hingedly connecting said plates, a latch keeper extended from said first plate, a pair of spaced lugs extended from said second plate, a headed pivot pin extended from said second plate, and a latch member mounted on said pivot pin for rocking movement in a direction normal to the said plates and being positioned between the said lugs.

4. A combination hinge latch comprising a pair of plates hingedly connected, one of said plates having an extended latch lug and the other of said plates having a pair of spaced movement limiting lugs and a pivot pin extended therefrom with an elongated latch bar mounted on said pivot pin for movement away from said plate and having a notched part for engagement with said latch lug on the other and first said plate and a part resting between the said spaced lugs, the said pivot pin having yieldable means normally urging said latch member against the said second plate.

5. A combination hinge latch comprising a pair of hingedly joined plates, a first plate of said pair having a latch keeper extended therefrom and a second plate of said pair having latch means mounted for rocking movement thereon in a direction substantially vertical thereto, means limiting the movement of said latching means in a plane parallel to said plate, and means yieldingly urging said latching means against said second plate in a vertical direction.
